UNITED STATES PATENT OFFICE

2,571,873

DISTANCE AND BEARING PLATE FOR
CANE MILLS

Francis Hegenbarth, Wilkes-Barre, Pa., assignor
to Vulcan Iron Works, Wilkes-Barre, Pa., a
corporation of Pennsylvania

Application July 12, 1946, Serial No. 683,241

6 Claims. (Cl. 308—9)

1

The present invention relates to improvements in cane mills and more particularly to distance and bearing plates for such cane mills.

The invention is for use in connection with the type of top roll bearing illustrated and described in the prior Patent No. 2,101,266 to J. J. Munson in which short and long lips are provided on the roll bearing with the long lip extending below the horizontal center line of the top roll trunnion and overlapping the same in such manner as to require both trunnions and top rolls and both top roll bearings to be lifted out of the mill housing whenever either of the top roll bearings is to be replaced.

An object of the invention is to provide means whereby this disadvantage is obviated and in which a removable filler plate is mounted in a space provided therefor in the mill housing laterally of the top roll bearing at the side adjacent the longer lip of the bearing, with means whereby such filler plate may be removed to give the top roll bearing latitude of a degree greater than the amount of the overlap whereby to free such top roll bearing from the trunnion in the mill housing.

A further object of the invention is to provide such a filler plate which will act in the capacity not only of a distance plate but also of a bearing plate for the top roll bearing enabling the top roll bearing to ride up and down upon the plate with a small amount of friction, the plate being made of a material suitable to reduce such friction and the plate being preferably of the softer material as the plate can be easily and conveniently replaced.

With the foregoing and other objects in view the invention will be more fully described hereinafter and more particularly pointed out in the appended claims.

In the drawings, in which like parts are denoted by the same reference characters throughout the several views,

Fig. 1 is a fragmentary vertical section of a cane mill showing the improved distance and bearing plate in accordance with the present invention as in place, and

Fig. 2 is a similar view showing the plate removed and the top roll bearing shifted sidewise.

Referring more particularly to the drawings, 10 designates generally the mill housing, 11 one of the top roll journals and 12 the top roll bearing therefor.

In accordance with the Munson patent this top roll bearing is made with a short lip 13 at one side and a long lip 14 at the other side.

2

The top cap is indicated at 15, the ram at 16 and the pressure plate at 17, these parts being removable in the usual manner from the mill housing.

5 In accordance with the present invention a filler plate 18 occupies a space provided therefor in the mill housing alongside the long lip 14 of the top roll bearing 12. This filler plate 18 serves as a distance piece and also as a bearing plate. It may be held removable in the housing in any appropriate manner. As shown, its lower edge is adapted to slidably fit into a recess 19 formed in the mill housing below the space which such plate is adapted to occupy. This recess 19 is shouldered on the side adjacent the journal 11 so as to retain the plate in proper position at its lower edge when the upper portion of such plate is affixed by the screws 20 to the mill housing. Such screws pass through 10 countersunk holes 21 in the upper portion of the plate 18 and into threaded sockets 22 in the mill housing.

15 The upper edge of the plate 18 is provided with one or more tapped sockets 23 to removably receive the lower threaded studs or ends 25 of lifting rods 24.

20 In the use of the invention, the left longer lip 14 overlaps the cylindrical journal 11 by a distance O. The thickness of the plate 18 and the space in the mill housing occupied by such plate is somewhat greater than this overlap O.

25 Fig. 1 shows the assembled position of the parts in which the plate 18 is in effect a side wall of the mill housing 10. In this capacity it forms a distance piece which accurately holds 30 the top roll bearing 12 to the contour of the top roll journal 11.

35 The arrangement will permit the removal of the top roll bearing 12 without the necessity of removing the top roll, both top caps with rams and both pressure plates. If the bearing in the out 40 hand housing, for instance, of the mill runs hot it may be removed without disturbing the parts in the right hand housing and without disturbing the top wall itself. To remove the hot bearing, the left hand top cap 15 with its ram 16 and pertaining pressure plate 17 over the affected top roll journal are all removed.

45 Thereafter the screws 20 which are now accessible are withdrawn and the screw lifting rod 24 is lowered and has its end 25 engaged in one of the tapped sockets 23, or two or more of such lifting rods 24 are so engaged with the plate 18. These rods 24 are then employed to lift the plate 50 out in the manner indicated in Fig. 2. The re-

moval of the plate creates a space or opening of a greater width than the overlap O laterally of the top roll bearing 12 into which this bearing may be moved by a sidewise and upward motion until the overlap O no longer impedes the lifting out of the bearing. The replacement of the bearing takes place in the reverse order.

Such procedure will obviate the necessity of removing any of the parts as the top cap and ram with pressure plate on the right hand housing and the top roll shaft will at all times remain in position.

It will therefore be obvious that the improved arrangement results in considerable saving of time which is a very essential factor in the cane mill on the continued operation of which depends the economy of production and the uninterrupted operation of the other departments of manufacture in the sugar factory.

The plate 18, besides serving as a distance plate for the removal of the top roll bearing 12, has another useful purpose, that is of serving as a pressure plate, and for this purpose it is preferably made of a metal suitable to reduce friction between the plate 18 and the top roll bearing 12. In case of wear, the plate 18 can be easily and conveniently replaced.

Although I have described and illustrated herein in the best form of the invention known to me at this time, it will be understood that the application exhibits only one mechanical embodiment of which the invention is susceptible and I reserve the right to all such modifications and changes as may come within the scope of the following claims.

I claim:

1. For use with a cane mill housing having therein a vertical recess adapted to receive and support a top roll journal the combination with said mill housing and journal of a top roll bearing having at one side a short lip and at the other side a long lip, said long lip adapted to extend down below the horizontal center line of the roll journal and having a part overlapping said journal, the width of said bearing being less than the width of said vertical recess thereby defining a space between said bearing and said mill housing adjacent the long lip, and a filler plate removably received in said space, the length of said plate and the depth of said space being greater than the length of said long lip whereby said filler plate overlaps the long lip of said bearing.

2. The combination of claim 1 characterized by the fact that fastening means is provided to secure said filler plate to said mill housing.

3. The combination of claim 1 characterized by the fact that an area in said vertical recess lying above said journal and bearing defines an open space through the top of the mill housing to per-

mit the upward withdrawal of said filler plate and the subsequent upward withdrawal of the bearing after said bearing has been slid laterally into the space previously occupied by the removed filler plate thereby enabling the long lip portion of said bearing to clear the journal.

4. The combination of claim 1 characterized by the fact that said filler plate is constructed and arranged to receive a lifting means by which the same may be lifted out of its space in the vertical recess of said mill housing.

5. In a cane mill a housing having a lateral vertical recess therein for receiving a roll journal, the combination with said roll journal of a removable top roll bearing having a long lip parallel to and disposed adjacent but removed from a wall of said lateral recess in said mill housing, a filler plate removably mounted in said recess and lying between the wall thereof being spaced from but proximate to said long lip of said bearing, the area between the wall of said vertical recess and said long lip defining a space the depth of which is greater than the length of said long lip for receiving the lower edge of said filler plate, and a removable fastening for holding the upper portion of said plate rigidly to said housing.

6. In a cane mill having a top roll journal, a top roll bearing therefor having short and long lips with the long lip adapted to extend below the horizontal diameter of the journal with a portion of said lip adapted to overlap the journal below the horizontal diameter of said journal, a mill housing having an open-ended recess for receiving the journal and its top roll bearing, said recess being wider than the top roll bearing to permit the top roll bearing to move relatively down upon said journal with the long lip clearing the horizontal diameter of said journal and thereupon to move laterally in the recess to cause the top roll bearing to conform to the journal with the inner lower part of the long lip overlying the journal below its horizontal diameter whereby a space is left in the recess outwardly of the longer lip, and a distance and bearing plate removably mounted in said space substantially filling said space to prevent lateral backing off of the longer lip from said journal.

FRANCIS HEGENBARTH.
